UNITED STATES PATENT OFFICE.

WALTER H. WAKEFIELD, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

CHAIN CONTROL FOR AXMINSTER LOOMS.

Application filed October 12, 1926. Serial No. 141,183.

This invention relates to improvements in means for controlling the movements of the tube frame transporting chain for Axminster looms and it is the principal object of the invention to provide means for automatically arresting the chain so as to effect a change in the character of fabric being woven.

In Axminster looms it is customary to employ a number of tube frames which is a factor of the total number of picks or rows of tufts woven in the length of the rug, the chain being reversed about a line of symmetry in order to weave a rug having a number of picks greater than the number of tube frames employed. In certain designs it is desirable that the ends of the rugs shall be unlike, and this is achieved by weaving the center of the rug from the same or similar tube frames, the same tube frame supplying tufts for a large number of successive picks. At the present time this result is accomplished by a hand operation, that is, the pawl which advances the transporting chain is thrown out of action manually and the weaver must either count the number of picks of the loom during which the pawl is to be idle or he must have a string which will serve as a gauge to measure that part of the rug which is to be woven from the same tube frame.

It is an important object of my present invention to provide mechanical means for automatically counting the number of times the same tube frame is presented to the fabric in the weaving of the plain part of the rug and to resume the normal movement of the chain after the plain part is finished.

It is a further object of the invention to provide means for presenting each of a series of tube frames to the fabric for a plurality of successive picks, the different frames of the series forming tufts in different order so that the central part of the rug may have a comparatively simple figure, such for instance, as a checkerboard design.

It is a still further object of the invention to provide a device which may be employed to weave the heading customarily woven between successive rugs without requiring manual operation on the part of the weaver.

With these and other objects in view which will appear as the description proceeds, my invention resides in the combination and ar-

angement of parts hereinafter described and set forth in the claims.

In the accompanying drawings wherein I have shown a convenient embodiment of my invention,

Fig. 1 is a side elevation of a portion of an Axminster loom having my invention applied thereto,

Fig. 2 is an enlarged front elevation looking in the direction of arrow 2, Fig. 1,

Fig. 3 is an enlarged detail front elevation of a portion of the structure shown in Fig. 2,

Fig. 4 is a vertical section on line 4-4 of Fig. 3,

Fig. 5 is a fragmentary detail showing the construction of one of the upper sprockets and the manner in which the indicating tap-pet is received thereby,

Fig. 6 indicates a type of rug to be woven with the aid of my present invention.

Referring more particularly to Fig. 1 it will be seen that I have provided a loom frame 10 having a bottom shaft 11 to which is secured a cam 12 cooperating with a cam lever 13 pivoted as at 14. The rear end of said lever is attached to an upwardly extending link 15 connected to a bell crank lever 16 pivoted as at 17 to a part of the loom frame. A forwardly extending connector 18 attached to lever 16 is pivotally connected as at 19 (see Fig. 4) to a freely oscillating lever 20. An actuator pawl 21 is pivoted as at 22 to the lever 20 and is moved back and forth around pull-over shaft 23 as a center of rotation as the shaft 11 turns.

Said pull-over shaft 23 extends across the loom and has secured thereto at one end a ratchet 24 having a plurality of teeth 25 which cooperate with the pawl 21. A pair of sprockets 26, one at each end of the shaft 23 and one of which is shown in the drawings, are secured to said shaft 23 and cooperate with the transporting chains 27 made of double links 28 and single links 29 received by the teeth 30 of the sprockets. As customarily made there is a recess 31 formed between each pair of teeth 30. Tube frames 32, two of which are indicated in Fig. 1, are detachably secured to the chains and are moved thereby successively to a position under pull-over shaft 23.

The overhead structure for the loom comprises a beam 33 which supports upper guide sheaves 34 and relatively larger sprockets 35. Additional sheaves 36 may be provided 5 on the overhead work and the chain 27 is looped around said sheaves and sprockets as indicated in Fig. 1. Fig. 5 shows a fragment of one of the sprockets 35 where it will be seen that a recess 37 is formed between adjacent teeth 38, said recess 37 and recesses 31 of the sprockets on the pull-over shaft being usual and being employed herein for a purpose to be described.

In the normal operation of the loom cam lever 13 rises and falls and by means of intermediate mechanism the pull-over shaft is given an angular movement each pick of the loom corresponding to the space between adjacent teeth 30 on the sprocket 26. At 15 the conclusion of each angular movement of the pull-over shaft transferring arms, not shown but well understood, release the lowermost tube frame from the chain 27 and move the same downwardly toward the 20 fabric F where a tuft is incorporated in the cloth, after which the tube frame is returned to the chain. The mechanism thus far described is of common construction and may be operated in the usual manner.

My invention relates more particularly to 30 means for arresting movement of the chain 27 for a predetermined number of picks so that the tube frame which is immediately under the pull-over shaft 23 can be made 35 use of to supply a plurality of picks instead of being moved out of weaving position after the first tuft has been drawn therefrom. Accordingly, I secure to an arch 40 formed as part of the loom frame a bracket 41 on the lower end of which is a bearing 42 to receive the right hand end of shaft 43, the left hand end of which is free to 40 turn in a bearing 44 formed in a brace 45 usually employed to provide a pivot for the 45 left hand end of the pull-over shaft 23. A chain cylinder 46 has a hub 47 which is secured by means of a screw 48 to the shaft 43. A ratchet wheel 49 and hub 50 therefor are secured by means of set screw 51 to the shaft 50 43, said ratchet having teeth 52 shown clearly in Fig. 4.

In order to actuate the ratchet and chain cylinder I provide a pull pawl 53 which may conveniently be mounted on the stud 55 22 on which the main driving pawl 21 is mounted, said pull pawl 53 being urged toward the ratchet 49 by a light compression spring 54 the lower end of which is seated in a pocket 55 formed on the lever 20. A 60 shield 56 is provided for the pawl and has a hub 57 freely rotatable on shaft 43, said shield having a guard flange 58 and being attached by means of a connector 59 to arm 60 of a rocking lever 61 pivoted as at 62 65 on the rearwardly extending arm 63 of

bracket 41. A link 64 is connected at the lower end thereof as at 65 to the pawl 21 and at the upper end is connected as at 66 to a lever 67 pivoted as at 68 to the brace 45 and overlying the chain 69 on the sprocket 70 46.

The lower end of lever 61 has a shoe 70 which is positioned for engagement with tappets 71 formed on certain of the links 28 of the transporting chain 27 on that end 75 of the loom near the lever 61 and parts associated therewith.

In order to illustrate the operation of my invention I will describe the same in connection with an imaginary design, such as 80 shown in Fig. 6. The usual chain 27, when carrying a complete complement of tube frames, has 504 tube frames and is reversed about a central line of symmetry when the last tube frame of the set is reached, in 85 this way providing for 1008 picks or rows of tufts. The take-up of the loom may be set to give 7 picks or rows to the inch so as to produce a rug 144 inches long. It is by the use of the stated number of tube 90 frames nine feet in length that the ordinary 9 x 12 Axminster rug is woven.

The object of the present invention is to enable the use of the same number of tube frames as previously described but wherein 95 the rug will not be symmetrical about a center line, that is, each end will have a distinctive design in no way related to the other end. I will assume for instance that that portion of the rug indicated at A in Fig. 6 100 will require 240 picks or 240 tube frames and that the portion marked B will require the same number of tube frames, the part B being a distinctly different weave from the part A. There remains 24 tube frames 105 which can be used to weave the 528 picks found in the center of the rug and corresponding to the space C in Fig. 6. In order that the space C may have 528 picks it is necessary that each of the 24 tube frames allotted thereto shall weave 22 picks. In 110 order to accomplish this result the transporting chain 27 will be so built that when the first tube frame corresponding to section C is immediately under the pull-over shaft 23 the link 28 which is nearest the shoe 70 will 115 have a tappet 71 thereon to move the lever 61 in a clockwise direction around stud 62. The tube frame under shaft 23 moves to this 120 position while the pawl 21 is moving to the right as shown in Fig. 4 and as said pawl nears the right hand end of its motion the arm 60 through connector 59 will rock the shield 56 upwardly so that spring 54 will move the pawl 53 into operative position 125 with respect to the ratchet 49. As lever 20 returns to the left on the stroke which is normally idle so far as pawl 21 and the transporting chain are concerned the pull pawl 53 will move ratchet 49 one space and 130

a ball 80 on the chain 69 will appear under lever 67 to raise the latter. As said lever 67 is raised it will lift the pawl 21 by means of link 64 so that on the next or normally operative movement of lever 20 to the right said pawl 21 will be ineffective to turn the ratchet 24 and the pull-over shaft and the transporting chain will remain at rest. On each successive movement of the lever 20 to the left 10 as shown in Fig. 4 the chain cylinder 46 will be moved angularly to present another link of the chain 69 under lever 67. There will be a number of balls 80 on said chain 69 in order to keep the lever 67 in raised position, 15 the number necessary to give 22 picks being 21 balls. One of the links of the chain 69 will be without a ball, and when the chain 69 has made a complete revolution this link will come under lever 67 to permit the latter to 20 fall as lever 20 reaches its extreme left hand position. The pawl 21 will therefore fall into operative position with respect to the ratchet 24 and on the next movement of the pawl, which is to the right, the pull-over 25 shaft 23 will then be given an angular movement and another tappet 71 will be brought opposite the shoe 70 so that the operation just described will be repeated. The sequence of movements just described will 30 continue until the tappets 71 of the 24 chain links 28 have passed by shoe 70, after which shield 56 will remain down and the pull pawl will cease to actuate the chain 69, the 35 second set of 240 tube frames coming into action to complete the rug. In this way it is possible to divide the chain into three sections which will weave two end patterns A and B and the central plain pattern C.

In order to indicate that it is not necessary that the central portion C be entirely plain I have shown the same as of a modified checkerboard design, the first tube frame producing a number of squares 22 picks wide and 22 picks long extending across the fabric and the next tube frame having the squares alternated with those made by the first. By having the successive tube frames assigned to section C different it is possible to weave a rug the center of which is not plain. Obviously, the central portion C can be made in a variety of patterns depending upon the number of tube frames assigned to the weaving of this part of the rug.

While I have described the device in connection with a chain 27 supplied with a full complement of tube frames yet it is possible to use the same for rugs of lesser length than those described and it is also possible that when the last tube frame of the pattern has been reached a tappet 71 can be brought opposite shoe 70 so that the heading between rugs may be woven.

From the foregoing it will be seen that I have provided means for automatically controlling the pull-over shaft and transport-

ing chain of an Axminster loom so that a portion of the rug may be woven by a plurality of picks drawn from the same tube frame, the transporting chain remaining at rest while the tube frame provides a number of rows of tufts. Furthermore, it will be seen that this device can be employed to weave the headings between rugs and that by its use a rug of full length can be woven having a pattern which is not symmetrical in 75 its entirety about a central line.

A spring 80' is interposed between arm 60 and stand 41 and acts normally to hold the shield in the position shown in Fig. 4, and acts also to hold the shoe 70 of lever 61 in 80 the path of the tappets 71.

Having thus described my invention it will be apparent that changes and modifications may be made therein by those skilled in the art without departing from the spirit 85 and scope of the invention, and I do not wish to be limited to the details herein disclosed but what I claim is:

1. In an Axminster loom having a plurality of tube frames, a tube frame transporting chain, means to advance the same to present the tube frames one at a time to a position from which they are moved to the fabric being woven, and mechanism controlled by the transporting chain to arrest 90 the movement of the latter for a plurality of picks, to the end that the same tube frame may be operative on a plurality of successive picks of the loom.

2. In an Axminster loom having a plurality of tube frames, a transporting chain to move the tube frames successively to a position from which they are moved to weaving position, means to advance the chain with a step by step movement, and mechanism controlled by the chain to render said means inoperative to give the transporting chain a step by step movement, to the end that one of the tube frames may be operatively placed for a plurality of successive 100 picks of the loom.

3. In an Axminster loom having a plurality of tube frames, normally operative means to present a different tube frame to weaving position on each pick of the loom, 105 and mechanism under control of said means to render said means inoperative to present a different tube frame to weaving position each pick of the loom, to the end that one tube frame may be operative for a succession of picks.

4. In an Axminster loom having a plurality of tube frames, a transporting chain for the tube frames, a ratchet operatively connected to the chain, a pawl having a regular operative movement to actuate the ratchet, and mechanism controlled by the transporting chain to move said pawl to an operative position relatively to the ratchet.

5. In an Axminster loom having a plu-

4
rality of tube frames, a transporting chain for the tube frames, a ratchet operatively connected to the tube frames to move the latter, a pawl for the ratchet having a normally operative movement followed by an inoperative movement relatively to the ratchet, and mechanism controlled by the transporting chain and operative on the inoperative stroke of the pawl to move the latter out of operative position with respect to the ratchet.

5 6. In an Axminster loom having a plurality of tube frames, a transporting chain to move the tube frames successively to position, an angularly movable device operatively associated with the chain to move the latter, a reciprocating member to cooperate with the angularly movable device and having an operative movement with respect to the latter when moving in one direction and an inoperative movement with respect to the said device when moving in the opposite direction, and mechanism controlled by the transporting chain and effective during the inoperative movement of the reciprocating member to move the latter out of operative position with respect to the device, whereby said member will be ineffective to move the device when moving in either direction.

7 7. In an Axminster loom having a plurality of tube frames, a transporting chain for the tube frames, means to move said chain to present the tube frames successively to weaving position, a counter chain, a regularly moving normally ineffective actuator for the counter chain, means controlled by the transporting chain for the tube frames for rendering said actuator effective to ad-

vance the counter chain, and connections between said counter chain and the said first means to render the latter inoperative.

40

8. In an Axminster loom having a plurality of tube frames, a transporting chain for the tube frames, a counter chain, actuating means for said chains, connections controlled by the transporting chain to start the counter chain, and additional connections controlled by the counter chain effective when said counter chain starts its movement to arrest movement of the transporting chain.

45

9. In an Axminster loom having a plurality of tube frames, a transporting chain for the tube frames, a counter chain, means normally effective to give the transporting chain movements on successive picks of the loom, additional regularly moving means normally ineffective to give the counter chain movements, and mechanism operatively related to both chains whereby each can stop the movement of the other.

50

55

10. In an Axminster loom having a plurality of tube frames, a transporting chain for the tube frames, a counter chain, means normally effective to give the transporting chain movements on successive picks of the loom, additional regularly moving means normally ineffective to give the counter chain movements, and mechanism operatively related to both chains whereby each can stop the movement of the other and whereby the transporting chain can start the counter chain.
